[57] CLAIM

The ornamental design for an automotive hood scoop,
as shown and described.

DESCRIPTION

FIG. 1 is a perspective view of the exterior of an auto-
motive hood scoop showing my new design in place on
the hood of an automotive vehicle, the vehicle shown in
broken lines and being for illustrative purposes only and
forming no part of the claimed design;

FIG. 2 is a top plan view thereof;

FIG. 3 is a front elevational view thereof;

FIG. 4 is a right elevational view thereof;

FIG. 5 is a bottom plan view thereof;

FIG. 6 is a left side elevational view thereof; and

FIG. 7 is a rear elevational view thereof.
